UNITED STATES PATENT OFFICE.

RUDOLF MÜLLER-ZOLLINGER, OF OBERBURG, SWITZERLAND, ASSIGNOR TO MABAG,
THE LANGENTHAL MACHINE WORKS, LIMITED, OF LANGENTHAL, SWITZERLAND,
A CORPORATION OF SWITZERLAND.

GAS SINGEING DEVICE FOR YARNS OF ALL KINDS.

Application filed February 9, 1927, Serial No. 166,843, and in Switzerland February 12, 1926.

The subject-matter of this invention is a gas singeing-device, wherein the singeing-tube consists of annular elements or sections detachably placed one on another, spaces being provided between the adjacent elements or sections, which spaces open into the central bore of the tube and are connected with the gas-supply pipe.

As compared with known devices comprising a singeing-tube the improved device according to the invention has the advantage that in consequence of the described construction of the tube circular burner slots are provided and consequently flames are produced in the tube which completely fill up the cross-section of the central duct, so that the thread drawn through the device is singed uniformly on all sides. Another advantage is that the said slots can be cleaned much more easily than the small burner openings which were universally customary heretofore and which readily become choked and can be cleaned with difficulty.

Two embodiments of the invention are illustrated by way of example in the accompanying drawings, wherein:

Figures 1 to 4 show one singeing tube according to the invention,

Figure 1 being a vertical section taken on the line A—B in Figure 3,

Figure 2 a vertical section taken on the line C—D in Figure 3,

Figure 3 a horizontal section taken on the line G—F in Figure 1, and

Figure 4 a horizontal section taken on the line H—J in Figure 1;

Figures 5 to 8 show a second form of tube according to the invention,

Figure 5 being a vertical section taken on the line K—L in Figure 6,

Figure 6 a horizontal section taken on the line M—N in Figure 5,

Figure 7 a vertical section of a detail, and

Figure 8 a horizontal section showing a modified detail.

Figure 9 is a vertical sectional view of a detail showing the end faces of the adjacent sections disposed at substantially 90° from each other.

Referring first to Figures 1 to 4, the numeral 1 designates the detachable base of the singeing-tube which is attached to the wall 2. In the base 1 is formed a supply duct 3 for the gas which enters through the

branch pipe 4. The base carries a jacket 5 of the tube, which jacket is held by bolts 6 between the base and a cover plate 7. The jacket 5 closely surrounds the singeing tube which comprises annular sections or elements 8 arranged one on another. In the outer side of the sections 8 ducts 9 are provided which extend almost the entire height of the tube and are in open communication with the duct 3. The upper end of each duct 9 is closed. Between two adjacent elements or sections 8, whereof the upper sits on lugs 10 of the lower, there is a free annular gap or space 11 which in consequence of the conical shape of the end faces of successive sections taper towards the central bore or duct 13 of the burner. A slot 12 for the admission of the thread extends the entire length of the singeing tube. At the lower inner edges the sections 8, with the exception of the lowest, are provided each with a groove 14.

The described device operates as follows:—The gas enters into the chamber 3, distributes itself amongst the outer ducts 9 and then enters through the gaps or spaces 11 into the central duct or bore 13. In consequence of the described form of the spaces 11 a round flame filling the entire cross-section of the duct 13 and ending in a central jet of flame is produced in each of these spaces 11, so that every thread drawn through the device will be uniformly singed on all sides. The grooves 14 of the sections prevent the flames from being interrupted which might occur without these grooves owing to the draught caused by the threads pulled at a high speed through the burner. In consequence of the described construction the device also has the advantage that it can be readily taken apart and cleaned. Owing to the intermediate gaps or spaces 11 widening outwards the singeing-device can be cleaned with a burette without danger of stopping up the said spaces. The taking apart can be facilitated by making the jacket 5 in two parts.

Instead of being cylindrical, as shown in the drawing, the sections 8 may have any other convenient form. The end faces of the successive sections or elements may form an angle of up to 90° or more one with another, as illustrated in Fig. 9.

Referring now to Figures 5 and 6, in this

form the elements or sections have double walls, and between the end faces of the inner walls of two adjacent sections annular burner slots or gaps are left which place the 5 central duct of the singeing-tube in open communication with the gas-supplying space or duct between the walls of the sections.

The device shown in Figures 5 and 6 comprises a bracket 1 integral with the base 15 10 of the singeing-tube. In this base 15 the supply duct 3 for gas is provided. The base 15 has in addition two holes 16 serving for receiving bolts not shown; these bolts are for detachably connecting the base 15 with a 15 cover 17 and holding the elements or sections 18 between the base and cover. The cylindrical sections 18 have double walls, the outer walls 19 being connected with the inner walls 20 by radial ribs 21. The outer walls of 20 two adjacent elements are interconnected at 22 by a groove and tongue. Between the end faces of the inner-walls 20 of two adjacent elements 18 annular burner slots or gaps 23 are provided by recessing the one end face, 25 which slots place the central duct 24 of the singeing burner in open connection with the duct or space 25 between the outer and inner walls of the elements. In addition, a groove 26 is formed in the end face of the inner wall 20 of each element situated above 30 a slot 23. An admission slot 27 for the thread is provided along the entire length of the singeing burner.

The gas enters through the channel 3 into 35 the space 25 and passes through the slots 23 into the central duct or bore 24 of the burner. At each burner slot 23 a round flame filling the entire cross-section of the bore 24 is formed, which flames ensure that the thread 40 drawn through the burner shall be singed uniformly on all sides. The grooves 26 prevent the frames from being ruptured by the draught which is caused by the air flowing through the burner from below upwards and 45 which is increased by the thread moving at a high speed through the burner.

The modified detail shown in Figures 7 and 8 has the object of enabling secondary air to be admitted to the central bore or duct. 50 The inner and outer walls 19 and 20 respectively of each element are connected by radial ribs 28, whereof each rib and the walls connected by it are traversed by a duct 29 which enables the outer air to enter into the 55 central bore of the burner. Above the point where each duct 29 opens into the central bore there is formed in each element a groove 30 which facilitates the admission of air to the central bore by its preventing the air 60 entering through the ducts 29 from being cut off by the current of air and gas flowing through the central bore. The ducts 29 may be formed conically or as slots if desired, and they may be directed slantwise instead of 65 horizontally.

I claim:—

1. In a gas singeing-device, a singeing-tube comprising in combination a plurality of tubular elements detachably placed one on another, which elements are so shaped as to 70 leave between them spaces which open into the central bore of the tube, and at least one duct for connecting said spaces with a gas-supply conduit.

2. In a gas-singeing device, a singeing 75 tube comprising a plurality of tubular elements detachably placed one on another end to end, which elements are so shaped as to leave between them spaces which open into the central bore of the tube, and at least one 80 duct formed in the walls of said elements and extending substantially the entire length of the tube for connection to a gas supply pipe.

3. In a gas singeing-device, a singeing tube comprising in combination a plurality 85 of tubular elements detachably placed one on another end to end, which elements are so shaped as to leave between them annular slots which open into the central bore of the tube, and at least one duct for connecting 90 said spaces with a gas-supply conduit.

4. In a gas singeing-device, a singeing tube comprising a plurality of tubular elements detachably placed one on another end to end, which elements are so shaped as to 95 leave between them annular gaps which open into the central bore of the tube, and at least one duct formed in the walls of said elements and extending through said gaps substantially the entire length of the tube 100 for connection to a gas-supplying conduit, each of which elements has a groove formed in it above a gap at the bottom of it.

5. In a gas singeing-device, a singeing tube comprising a plurality of double-walled tubular elements detachably placed one on another end to end, which elements are so shaped as to leave between them spaces which open into the central bore of the tube, the space between the walls of 105 said elements serving as a duct for supplying gas to said spaces.

6. In a gas singeing-device, a singeing tube comprising a plurality of double-walled tubular elements detachably placed one on another end to end, which elements are so shaped as to leave between them annular gaps which open each into the central bore of the tube, the space between the walls of the elements being in open communication 115 with said gaps and serving for connecting them with a gas-supply conduit.

7. In a gas singeing-device, a singeing tube comprising a plurality of double-walled tubular elements detachably placed one on another end to end, the outer walls of which elements have a tongue on one element entering a recess in an adjacent element, which elements are so shaped as to 125 leave between them at their ends gaps which 130

open into the central bore of the tube, the space between the walls of which elements is adapted to supply gas to said gaps.

8. In a gas singeing-device, a singeing tube comprising a plurality of double-walled tubular elements detachably placed one on another end to end, which elements are so shaped as to leave between them at their ends gaps which open into the central bore of the tube, the space between the walls of which elements is adapted to supply gas to said gaps, each element having at least one rib connecting the inner and outer walls of the element, each of which ribs and the walls connected therewith is perforated by a duct for supplying air to the central bore.

9. In a gas singeing-device, a singeing tube comprising a plurality of double-walled tubular elements detachably placed one on another end to end, which elements are so shaped as to leave between them at their ends annular gaps which open into the central bore of the tube, the space between the walls of which elements serves to supply gas to said gaps, each element having at least one rib connecting the inner and outer walls of the element, each of which ribs and the walls connected therewith is

perforated by a duct for supplying air to the central bore, each of which elements has a groove above the outlet of its said duct into the central bore.

10. In a gas singeing-device, a singeing tube comprising in combination a base, a cover plate and a plurality of tubular elements detachably placed one on another end to end detachably between said base and cover plate, which elements are so shaped as to leave between them annular slots which open into the central bore of the tube, and at least one duct arranged to connect said slots to a gas-supply conduit.

11. In a gas singeing-device, a singeing tube comprising in combination a base having a gas-supply duct, a cover plate, and a plurality of tubular elements detachably placed one on another end to end detachably between said base and cover plate, which elements are so shaped as to leave between them gaps which open into the central bore of the tube, and at least one duct extending through said elements and connecting said gaps to said gas-supply duct in the base.

Signed at Berne, this 26th day of January 1927.

RUDOLF MÜLLER-ZOLLINGER.
